UNITED STATES PATENT OFFICE.

KARL E. PEILER, OF WEST HARTFORD, CONNECTICUT, ASSIGNOR TO HARTFORD-EMPIRE COMPANY, OF HARTFORD, CONNECTICUT, A CORPORATION OF DELAWARE.

APPARATUS FOR ANNEALING GLASSWARE.

Application filed November 2, 1925. Serial No. 66,180.

The invention relates to apparatus for annealing glassware, and it has particular relation to lehrs of the tunnel type through which articles of glassware are transported by a conveyor and in which they are subjected to varying temperature environments.

One of the objects of the present invention is to provide a lehr, of the character described, that may be quickly and easily assembled from a plurality of substantially similar cast metal sections which, when secured together in end-to-end relation, provide a very rigid and self-supporting structure having substantially gas-tight joints between the several sections.

Another object of the invention is to provide a lehr constructed of a plurality of integral cast metal sections, each section of which is provided with means for permitting certain portions thereof to move relative to each other with changes in temperature.

In the accompanying drawings:

Figure 1 is a diagrammatic vertical longitudinal sectional view of a tunnel lehr embodying the invention;

Fig. 2 is a perspective view illustrating more in detail the construction of the individual sections and the manner of securing them together; and

Fig. 3 is a view similar to Fig. 2 illustrating a modified form of tunnel section.

Referring to the drawings, a lehr is shown diagrammatically in Fig. 1 as comprising in general a metallic sectional tunnel 1, supported by a frame structure 2 and having a heating flue 3 extending longitudinally therebeneath, through which heated gases from a firebox 4 are caused to flow by a draft-producing device 5, specifically a suction fan, disposed above the exit end of the tunnel. Dissipation of heat from the entrance end and the intermediate portions of the tunnel 1 is retarded by a surrounding casing of insulating material 6, such as powdered kieselguhr or the like. The cooling of the ware is accelerated towards the exit end of the tunnel by omitting the insulation so as to expose the metallic walls of the tunnel to the cooling influence of the outer atmosphere.

Ware is transported through the tunnel 1 by an endless conveyor 7 of open woven wire structure, the ware-bearing strand of which traverses the tunnel, being supported therein directly by the flat bottom thereof, and also traversing a ware sorting table 8. The

idle strand of the conveyor returns to the entrance end of the tunnel beneath the lehr, being supported at intervals therebeneath by rollers 9. The conveyor 7 is driven by a driving mechanism 10 of any suitable design, but preferably consisting of a pair of rollers which frictionally grip the conveyor between them.

According to the invention, the tunnel 1 is constructed of a plurality of integral cast metal sections 11, preferably of cast iron, each section having a bottom 12, side walls 13 and a top 14 and being formed with peripheral flanges 15 at each end, by means of which the sections are bolted together to form a rigid self-supporting structure. The abutting faces of the flanges 15 are preferably machined to provide very smooth surfaces, so that when the sections are secured together, the joints therebetween will be substantially gas-tight.

Each of the sections 11 is also provided with a horizontal partition 16 which is formed integrally with the side walls 13 and which divides the interior of the section into an upper passageway 17 for the ware and a lower passageway 18 for a temperature-controlling medium. This medium may be either hot gases or cooling air, but for the purpose of illustration the hot gases from the fire box 4 are referred to in the present case. The partition 16 forms the floor of the tunnel proper, and constitutes the sole support for the ware-bearing strand of the conveyor 7. The lower surface of the partition 16 is preferably formed with a plurality of transverse re-enforcing ribs 19 to minimize warping through changes in temperatures.

In order to provide further against distortion of the tunnel, when subjected to the heat of annealing, the bottom 12 and the top 14 of each section, at the hot portions of the lehr, are formed with longitudinal slots 20 and 21 respectively which permit the portions thus divided to move relative to each other. A strip 22 of sheet metal covers the slot 20 in the top and prevents the insulating material 6 from obtaining access to the interior of the tunnel.

In the modification illustrated in Fig. 3, the top of each section comprises a separate plate 23, the longitudinal edges of which are cut away, as indicated at 24, for engagement with the side walls 13. The cut-away

portions 24 prevent lateral displacement of the top and are of sufficient width to permit the top to expand under the action of heat. The gaps between the tops of the adjacent 5 sections are covered by transverse strips 25 to prevent the insulation from obtaining access to the tunnel.

From the foregoing it will be apparent that a very rigid and self-supporting tunnel 10 structure is provided, and one that may be assembled with a minimum expenditure of time and labor.

The illustrated embodiment of the invention may be modified in construction and arrangement without departing from the scope 15 of the invention, as defined in the appended claims.

I claim as my invention:

1. Apparatus for annealing glassware including a tunnel comprising a plurality of unitary metallic sections arranged in end-to-end abutting relation with respect to each other and rigidly secured together.

2. Apparatus for annealing glassware comprising a tunnel consisting of a plurality of integral cast iron sections arranged in end-to-end abutting relation with respect to each other and rigidly secured together.

3. Apparatus for annealing glassware comprising a tunnel consisting of a plurality of cast iron sections having flanged ends and arranged in end-to-end abutting relation with respect to each other with their adjacent flanges rigidly bolted together.

35 4. Apparatus for annealing glassware comprising a tunnel consisting of a plurality of cast iron sections having flanged ends and rigidly bolted together in end-to-end abutting relation, the contiguous surfaces of 40 said abutting sections being provided with a smooth finish to provide substantially gas-tight joints.

5. Apparatus for annealing glassware comprising a tunnel consisting of a plurality of unitary cast iron sections each having a flue portion formed integrally therewith, the said sections being rigidly secured together in end-to-end abutting relation.

6. Apparatus for annealing glassware comprising a tunnel consisting of a plurality of unitary metallic sections each having a partition therein dividing the interior thereof into a passageway for ware and a passageway for a temperature-controlling 55 medium, the said sections being adapted to be rigidly secured together in end-to-end abutting relation.

7. Apparatus for annealing glassware comprising a tunnel consisting of a plurality of unitary metallic sections each having a partition therein dividing the interior thereof into a tunnel portion and a flue portion, the said sections being adapted to be rigidly secured together in end-to-end abutting 60 relation, and a conveyor supported by

said partition for transporting articles of glassware through said tunnel.

8. Apparatus for annealing glassware, including a tunnel comprising a plurality of metallic sections arranged in end-to-end relation, each of said sections having a duct 70 provided therein and adapted to cooperate with the ducts in the other sections to form a longitudinal flue for the passage of a temperature-controlling medium.

75 9. Apparatus for annealing glassware, including a tunnel comprising a plurality of cast metal sections, rigidly secured together in end-to-end relation, each of said sections having a duct cast integrally in a wall thereof, and adapted to cooperate with the ducts in the other sections to form a flue extending longitudinally of the tunnel for the passage of a temperature-controlling medium.

80 10. Apparatus for annealing glassware comprising a tunnel having a metallic floor and side walls and top integral with said floor, said top being divided longitudinally to permit of independent movement of the 90 portions so divided with changes in temperature.

85 11. Apparatus for annealing glassware comprising a tunnel section having a metallic wall and a flue formed integrally with 95 said wall.

12. Apparatus for annealing glassware comprising a tunnel section having a metallic wall, a flue formed integrally with said wall, and means for preventing said wall 100 from warping with changes in temperature.

13. Apparatus for annealing glassware comprising a tunnel having a metallic floor, and a flue formed integrally therewith, and having a slot in one of its walls to accommodate expansion and contraction with 105 changes in temperature.

14. Apparatus for annealing glassware embodying a tunnel comprising a plurality of cast iron sections rigidly secured together in end-to-end abutting relation, each of said sections having a floor, side walls formed integrally therewith, a top formed 110 integrally with said walls, and a flue formed integrally with said floor.

15. Apparatus for annealing glassware embodying a tunnel comprising a plurality of cast iron sections rigidly secured together in end-to-end abutting relation, each of said sections having a floor, side walls formed 120 integrally therewith, a top formed integrally with said walls, and a flue formed integrally with said floor, said top and a wall of said flue being divided longitudinally thereof to permit of relative movement of the portions thus divided with changes in temperature.

16. Apparatus for annealing glassware embodying a tunnel comprising a plurality of integral cast iron sections of rectangular 125

cross section rigidly secured together in end-to-end abutting relation, each of said sections having a horizontal partition dividing the interior thereof into a passage-
way for the ware and a passageway for a temperature-controlling medium, each of said passageways having a wall divided longitudinally thereof to accommodate relative movement of the portions thus divided
10 with changes in temperature.

17. Apparatus for annealing glassware,

including a tunnel comprising a plurality of self-supporting metallic sections arranged in end-to-end relation, each of said sections having a passageway for ware and a passageway for a temperature-controlling medium, said passageways being separated by a wall common to both of said passageways.

Signed at Hartford, Conn., this 31st day of October, 1925.

KARL E. PEILER.
